FLUID IMPREGNATING DEVICE

Max J. Belmont, New York, N. Y.

Application July 19, 1937, Serial No. 154,402

5 Claims. (Cl. 299—84)

This invention relates to a fluid impregnation device and more specifically to a device to be used in impregnating, with solvents, etc., water to be used in washing the human body or parts thereof.

In general, it is an object of the invention to provide a device of the character described, which will efficiently perform the purposes for which it is intended, which is simple and economical of construction, which can be expeditiously, conveniently and safely manipulated, and which can be readily manufactured and assembled.

Another object of the invention is to provide an impregnating device which conserves the impregnating matter; to provide such a device wherein the impregnating material, as it dissolves, is not in the main path of the fluid which is being dispensed; and to provide such a device which may be detachably added to a shower bath.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention, reference should be had to the following detailed description, taken in connection with the accompanying drawing, in which:

Figure 1 is a plan view of a device embodying one form of the invention;

Fig. 2 is a view in elevation, partly in section and partly cut away, of the device shown in Fig. 1;

Fig. 3 is a view of the device shown in Figs. 1 and 2 taken along the line 3—3 of Fig. 2; and

Fig. 4 is a side view of a modification of one of the elements of the device.

Heretofore there have been difficulties present in connection with apparatus which was intended to introduce material which dissolved or mixed with water to be used in bathing. One trouble was that more material dissolved than was necessary. This raised the cost of operation because bath salts are expensive. It also required constant refilling—a time-consuming nuisance. Devices embodying the present invention have done away with these and other drawbacks and have permitted the introduction of various materials at rates suitable for each.

In the drawing, 10 denotes a casing which may be of almost any shape. It is shown as a hollow

circular cylinder providing a chamber 12 therein. An inlet and an outlet are provided. The inlet 14 may be at the upper end and may comprise a tube positioned centrally of one end and threaded on its inner surface. The outlet 16 may be a tube leading from the other end and positioned eccentrically with respect to the axis of the device. It may be threaded on its outer surface outside of the device.

Means are present which provide a second chamber. Thus, a hollow plug or tube 18 having threads 20 at one end is held within the chamber 12 by those threads which are in engagement with threads 22 on the inside of an opening 24 in the casing. Opening 24 may be 15 on the same side of the device as outlet 16. The tube 18 is perforated with a plurality of openings 26. Means are provided for preventing passage through the openings 26 of solid material from the chamber 28 within the plug 18. This may 20 take the form of a cylindrical wire mesh 30 positioned on the inside of the tube 18. The inner end of the plug may have a removable cap 32 which may or may not have openings 34 therethrough. There is a cap 36 attached to the plug 25 outside of casing 10.

Any material which may be desired to impregnate the water flowing through the device is put into the plug 18. The plug is positioned so that the main line of flow between the inlet 14 and 30 the outlet 16 does not pass through the plug. The size and number of the openings 26 depend upon the amount of material which is to be added to the water and upon the solubility of the material if the addition thereof to the water depends 35 upon its solubility. If the water is not to pass through the entire length of the plug, all of the plug need not be within the chamber 12. Openings 26, however, should communicate with chamber 12. It is not necessary that the inlet and 40 outlet be on opposite sides of the device but this form is convenient.

A device with the form shown may be attached to an ordinary shower, the inlet 14 being screwed on to the shower inlet pipe (not shown). The 45 shower spray head, or the conduit leading thereto, (neither shown), may be attached to the outlet 16. The position of the parts of the shower are usually such that inlet 14 will be on the upper side and outlet 16 on the lower side, although this 50 is not necessary. The openings 26 may be at the lower end of the tube so that as the material in the tube is used, it falls toward the openings. In case the parts are not positioned so as to maintain material near the openings, or in case the 55

material is not dispensed rapidly enough, or for any other reason, the cap 32 may have openings 34 which lead to the chamber 12 so that water may flow or seep through the entire length of the plug.

The size of the openings may be controlled by means, for example, those shown in Fig. 4. There may be an outer sleeve 38 around at least a portion of the tube 18. This sleeve may have openings 126 therethrough which, upon the rotation of the sleeve, register wholly or in part with openings 26 of the tube. The sleeve may be positioned on the inside of the tube and may be used in conjunction with the screen 30 or it may have a screen in or over each of the openings 126.

The operation of the device will be apparent from the foregoing description. When it is first put in use, the plug 18 is removed by unscrewing it and it is filled with any desired material. The plug is then reinserted into the device and water or other liquid is passed therethrough. The main flow of the liquid does not pass through the materials in the plug. A certain amount of liquid filters in and out of the openings 26, taking along a desired amount of the material. This action may be brought about by the solution of the material or its change into very small particles. The screen 30 prevents solid material other than minute particles from being swept out. After the material has been used up, the plug may be refilled.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and useful and desire to secure by Letters Patent is:

1. In a water-impregnating device, the combination comprising means providing a chamber, inlet means leading into said chamber, outlet means leading out of said chamber, means providing a second chamber, inlet and outlet means for said second chamber and in communication with said first chamber and not in the direct line of flow of the first-mentioned chamber and spaced from the direct line of flow between said inlet and outlet means of the first-mentioned chamber, and means adapted for preventing the passage of solid material through said inlet and outlet means of said second chamber while said last-mentioned means are in operation, said

second chamber being at least in part positioned within said first chamber.

2. In a water-impregnating device, the combination comprising means providing a chamber, inlet means leading into an upper surface of said chamber, outlet means leading out of a lower surface of said chamber, a removable hollow plug positioned in the lower surface of and extending into said chamber, there being perforations in the wall of said plug leading between said chamber and the interior of said plug, screening across said perforations, none of said perforations being in the direct line of flow through said chamber and none of said perforations being in the direct line of flow into said chamber.

3. In a water-impregnating device, the combination comprising means providing a chamber, inlet means leading into an upper surface of said chamber, outlet means leading out of a lower surface of said chamber, a removable hollow plug positioned in the lower surface of and extending into said chamber, there being perforations in the wall of said plug leading between said chamber and the interior of said plug, none of said perforations being in the direct line of flow through said chamber and none of said perforations being in the direct line of flow into said chamber.

4. In a water-impregnating device, the combination comprising means providing a chamber, inlet means leading into an upper surface of said chamber, outlet means leading out of a lower surface of said chamber, a removable hollow plug positioned in the lower surface of and extending into said chamber, there being perforations in the wall of said plug leading between said chamber and the interior of said plug, none of said perforations being in the direct line of flow through said chamber and none of said perforations being in the direct line of flow into said chamber, the walls of said plug having a direction which is at an angle with the horizontal and said perforations being at the lower end of said plug.

5. In a water-impregnating device, the combination comprising means providing a chamber, inlet means leading into an upper surface of said chamber, outlet means leading out of a lower surface of said chamber, a removable hollow plug positioned in the lower surface of and extending into said chamber, there being perforations in the wall of said plug leading between said chamber and the interior of said plug, and positioned at one end of said plug, there being an opening into said chamber through the other end of said plug, said plug being positioned so that the flow between said opening and said perforations is not in the main line of flow in said chamber and so that said opening is not in the main line of flow into said chamber.

MAX J. BELMONT.
